UNITED STATES PATENT OFFICE.

JAMES S. COPELAND, OF HARTFORD, CONNECTICUT, ASSIGNOR TO POPE MANUFACTURING COMPANY, OF JERSEY CITY, NEW JERSEY, A CORPORATION OF NEW JERSEY.

MOTOR-CYCLE.

SPECIFICATION forming part of Letters Patent No. 764,113, dated July 5, 1904.

Application filed December 18, 1903. Serial No. 185,672. (No model.)

To all whom it may concern:

Be it known that I, JAMES S. COPELAND, a citizen of the United States, residing at Hartford, in the county of Hartford, in the State of Connecticut, have invented certain new and useful Improvements in Motor - Cycles, of which the following is a specification, reference being had to the accompanying drawings, forming a part hereof.

10 This invention relates to motor-vehicles of the class or type commonly known as "motor-cycles," including particularly motor - propelled bicycles and tricycles; and it has for its object to improve the mounting of the motor in the frame of the cycle, both with respect to the location of the motor in the frame and to the means for securing the motor in the frame, involving also the construction of the frame and the relative arrangement of the several 15 members thereof.

One particular object is to provide for the location of the motor where it will be least objectionable to the rider and where also its weight will contribute to the stability of the 20 cycle and will assist in securing good tractive effect, while at the same time the length of wheel-base of the cycle is increased without the undesirable appearance of a long open frame.

25 Another particular object is to secure for the frame great strength without undue increase in the weight of the materials employed.

A further object is to provide for the secure 30 attachment of the motor to the frame with economy of space and without the use of clamps or other devices which add weight and detract from the appearance of cycles of this character.

35 The invention will be more fully described hereinafter with reference to the accompanying drawings, in which for purposes of explanation it is illustrated as embodied in a convenient and practical form, and in which—

40 Figure 1 is a view in side elevation of a motor-bicycle which embodies the invention, some parts being broken away to save space and others being removed to prevent confu-

sion. Fig. 2 is a detail view, in side elevation, of the lower portion of the frame with the 50 crank-shaft and its bearings, the motor and the intermediate shaft and its bearings removed. Fig. 3 is a vertical section of the lower portion of the motor-casing, and Fig. 4 is an under side view of the lower portion of 55 the motor-casing.

In general appearance the frame of the cycle substantially resembles that of the ordinary diamond frame, the main upper reach or member a , the steering-post tube or member a' , and the main lower reach or member a'' being arranged substantially as in the ordinary diamond frame, except that the main lower reach or member is curved upwardly at its rear or lower end, as shown at a^3 in 60 Figs. 1 and 2. The seat-post or member a^4 is extended downwardly from the rear end of the main upper reach or member a and is brazed, as usual, at its lower end to a crank - shaft bracket a^5 , which in the improved frame is 65 provided on its lower and forward side with an eye a^6 , through which the main lower reach or member a'' is extended and in which it is brazed. At its rear end the main lower reach or member is brazed to an intermediate bracket 70 a^7 , from which the lower rear fork-tubes a^8 are extended rearwardly, as usual, and from which one or more stays or braces a^9 are 75 extended upwardly to the upper rear fork-tubes or stays a^{10} , which are secured at their upper 80 forward ends at or near the junction of the members a and a' and at their lower ends to the corresponding lower fork-tubes a^8 . The steering-post tube receives, as usual, the steering-fork b and the steering-shaft c , the latter having secured thereto the usual handle-bar d . The saddle or seat e for the rider may be supported, as usual, by a seat-post which enters the seat-post tube a^4 . It will be observed that the extension of the main lower tube a'' downwardly and rearwardly through the eye a^6 of the pedal - shaft bracket, its curvature upwardly to the point of support of the intermediate bracket, and the connection of the latter by the stays or braces a^9 with the upper rear fork-tubes or stays a^{10} not only gives 85 90 95

great length to the rear portion of the frame, but provides a structure which it is practically impossible to distort. Moreover, the described construction of the frame is particularly well adapted for its main purpose—viz., the firm support of the motor in rear of the rider, where the heat from the motor is not objectionable, where oil flying from the motor is not likely to be thrown upon the clothing of the rider, and where, in conjunction with the location of the rider's weight, it increases the stability of the cycle and secures the maximum traction effect. The advantages last referred to will more clearly appear when it is understood, as will be readily seen upon reference to the drawings, that the pedal-shaft f is located above the main lower member a^3 , while the motor g is mounted in rear of the pedal-shaft, with its main shaft g^8 at least as low as the pedal-shaft, placing the weight of the motor, which is supported in the lower curved portion a^3 of the main lower member a^2 , very low in the frame. The low positioning of the motor and of its main shaft g^8 also permits the intermediate bracket a^7 to be brought into line with the main shaft of the motor and the axis of the rear wheel and prevents any tendency to distortion of the rear portion of the frame through the driving connections. In the drawings such connections are shown as comprising a sprocket-pinion g^{12} on the shaft g^8 of the motor, a large sprocket g , a small sprocket g' on the intermediate shaft g^2 , which is supported in the intermediate bracket a^7 , and a large sprocket g^3 on the hub of the driving-wheels g^4 , corresponding sprocket-chains g^5 and g^6 being provided for the transmission of power from one sprocket-wheel to the next; but it will be understood that the driving connections can be arranged as preferred and form no part of the present invention.

The motor g rests by its own weight in the seat provided therefor by the curved rear portion of the main lower member a^2 , the curvature of such member conforming in part to the curvature of the main lower portion of the motor-casing. For the attachment of the motor to the frame there are provided on the frame three tenons, one of which, a^{13} , is brazed to or forms a part of the pedal-shaft bracket a^5 , while another, a^{14} , is likewise brazed to or forms a part of the intermediate bracket a^7 , and the third a^{15} is brazed to the upper side of the curved portion a^3 of the main lower member a^2 . The main lower portion g^x of the motor-casing has mortises g^{13} , g^{14} , and g^{15} machined therein to receive the corresponding lugs or tenons a^{13} , a^{14} , and a^{15} , respectively, thus allowing the motor-casing to lie closely on the lower frame-tube with a maximum economy of space, while no portion of the frame itself is weakened by any sort of cutting to accommodate the motor. When the motor is in place, it may be secured, if neces-

sary, by bolts extended through the lugs and tenons and the walls of the mortises, as indicated at n^{13} , n^{14} , and n^{15} , respectively. The motor is thus securely held in position without the use of additional clamps or subframe-work of any character.

It will be understood that the details of construction and arrangement can be varied more or less from what is shown in the accompanying drawings, as may be necessary to meet the requirements of different structures, without departing from the spirit of the invention.

I claim as my invention—

1. A motor-cycle frame of substantially diamond shape having a seat-post tube, a crank-shaft bracket at the lower end of said seat-post tube and provided with an eye and a main lower member extended through said eye and curved to form a seat for a motor, substantially as shown and described. 80

2. A motor-cycle frame of substantially diamond shape having a lower member curved in rear of the pedal-shaft bracket to form a seat for a motor, an intermediate bracket carried by said member, and a stay extended from said bracket to the upper rear fork-tubes, substantially as shown and described. 90

3. A motor-cycle frame of substantially diamond shape having a lower member curved in rear of and below the pedal-shaft bracket to form a seat for a motor, an intermediate bracket carried by said member, and a stay extended from said bracket to the upper rear fork-tubes, substantially as shown and described. 95

4. A motor-cycle frame having a main lower member curved to form a seat for a motor and provided with lugs or tenons in combination with a motor-casing having mortises to engage said lugs respectively, substantially as shown and described. 100

5. A motor-cycle frame having a main lower member curved to form a seat for a motor and provided with lugs or tenons in combination with a motor-casing having mortises to engage said lugs respectively, the walls of said mortises and said lugs or tenons being perforated to receive bolts to secure the motor in place, substantially as shown and described. 110

6. A motor-cycle frame of substantially diamond shape having a lower member curved in rear of the pedal-shaft bracket to form a seat for a motor, and lugs on said seat, in combination with a motor-casing adapted to said seat and having mortises to engage said lugs, substantially as shown and described. 115

7. A motor-cycle frame of substantially diamond shape having a lower member curved in rear of and below the pedal-shaft bracket to form a seat for a motor, and lugs on said seat, in combination with a motor-casing adapted to said seat and having mortises to engage said lugs, substantially as shown and described. 125

8. A motor-cycle frame of substantially dia-

mond shape having a main seat-post tube, a main lower member curved to form a seat for a motor, a pedal-shaft bracket connecting the last-named member and said seat-post tube, 5 an intermediate bracket carried by said last-named member, and lugs on said brackets and the curved portion of said member, in combination with a motor-casing mortised to en-

gage said lugs, substantially as shown and described.

This specification signed and witnessed this 12th day of December, A. D. 1903.

JAMES S. COPELAND.
